SERPENT PUPPET

Juanita A. Casey and Kathleen L. Johnson, Del City,
Oklahoma (both of 7055 Lennox, Apt. 5, Van Nuys, Calif.
91405)

Filed Jan. 28, 1975, Ser. No. 544,928

Term of patent 7 years

Int. Cl. D21—01

U.S. Cl. D34—2 R

FIG. 1 is a perspective view showing the top portion of the head, including the facial characteristics, and generally the rear portion of a serpent puppet showing our new design.

FIG. 2 is a perspective view showing the bottom portion of the head and generally the front portion of the serpent puppet design of FIG. 1.

We claim:

The ornamental design for a serpent puppet, substantially as shown and described.
